UNITED STATES PATENT OFFICE.

ERNEST C. RIMPLE, OF PORT ORCHARD, WASHINGTON.

DRINKING-STOPPER.

1,260,813.

Specification of Letters Patent. Patented Mar. 26, 1913.

Application filed November 4, 1916. Serial No. 129,499.

To all whom it may concern:

Be it known that I, ERNEST C. RIMPLE, a citizen of the United States, residing at Port Orchard, in the county of Kitsap and 5 State of Washington, have invented certain new and useful Improvements in Drinking-Stoppers; and I do hereby declare the following to be a full, clear, and exact description of the invention, such as will enable 10 others skilled in the art to which it appertains to make and use the same.

This invention relates to improvements in drinking stoppers.

The object of this invention is to provide 15 a stopper of this character which may be inserted in a bottle of any type and the contents of the bottle drunk therefrom thus obviating the necessity of a glass, cup or the like.

20 A further object of this invention is to provide a stopper which when inserted in a bottle permits the person or persons using the same to readily drink from the bottle without the necessity of taking the bottle 25 from the lips to swallow, due to the fact that the stopper is provided with an air passage which communicates with the atmosphere and mouth of the user whereby air may be drawn into the mouth to prevent a 30 vacuum from being formed therein and also to permit air to be drawn into and forced into the bottle to replace the liquid displaced therefrom.

35 A still further object of this invention is to provide a simple, practical, and comparatively inexpensive device of this character and one that can be manufactured and sold at a small cost.

With these and other objects in view the 40 invention consists in the novel combination and arrangement of parts hereinafter more fully described and pointed out in the claims hereto appended.

In the drawings:

45 Figure 1 a fragmentary portion of a bottle with my improved stopper therein, and

Fig. 2 is a vertical sectional view of the stopper.

Like numerals of reference designate corresponding parts in all the figures of the drawings.

Referring more particularly to the drawings, the numeral 1 designates a portion of a bottle of the usual type having the neck 55 portion 2 which has a beaded flange 3.

My improved drinking stopper comprises

in its construction the cylindrical extension 4 having its upper end enlarged as at 5, which enlarged portion is reduced at its upper end as at 6 forming a shoulder 7, 60 which shoulder limits the movement of the stopper in a person's mouth.

The upper portion 5 of the cylindrical extension 4 is offset laterally as at 8 to provide a shoulder 9, the purpose of which 65 will be more fully hereinafter described.

The cylindrical extension 4 and enlarged portion 5 is constructed of wood, glass, metal or the like, and has secured thereto a cork 10 which cork is of a tapered formation and 70 adapted to have its enlarged end in abutting engagement with the under side of the shoulder 9. The cork 10 is adapted to form an air tight connection between the stopper and bottle neck when inserted therein. 75

The enlarged portion 5 is provided with a diagonally extending bore 11 having its lower end opening out through the laterally extending portion 8 and its upper end opening out through the end of the tapered portion 6 of the enlarged portion 5, thus permitting the portion 6 to be placed between the lips of a person's mouth and the contents of the bottle drunk therefrom without the necessity of removing the bottle 80 from the lips. As an inlet of air may pass through the diagonally extending bar into the mouth of the user thus permitting the contents of the bottle to run freely into the mouth of the user due to the fact 85 that the air being drawn in through the opening so as to replace the contents being drawn from the bottle. 90

The diagonally extending opening 11 also permits a person when using the bottle to 95 readily draw air into his mouth thus preventing a vacuum from being created therein. It is to be noted that by this construction, air may be freely drawn into the mouth and a vacuum prevented from forming therein, and also air may be urged into the bottle to displace the liquid and to replace the liquid being displaced therefrom by the swallowing of the user. 100

What is claimed is:

1. A drinking stopper comprising a bottle engaging portion and a lip portion, and having a diagonal passage extending through the lip portion to permit of the inlet of air into the bottle. 105

2. A drinking stopper comprising a cylindrical body, an enlargement formed at one 110

end of the body, said enlargement having its upper end tapered, a cork arranged around the extension below the enlargement, and said enlargement provided with 5 a diagonal opening, substantially as described.

3. A drinking stopper comprising a cylindrical body, the upper end of the body being enlarged and provided with a lateral offset 10 portion, said enlargement provided with a diagonally extending air opening, and a cork surrounding the cylindrical body below the enlargement, said enlargement tapering exteriorly to provide a shoulder to 15 limit the insertion of the stopper in a per-

son's mouth, said air opening communicating with the atmosphere to permit of an inlet of air into the mouth of the user so that the air in the mouth of the user will replace the contents being drawn from the bottle 20 thus permitting the contents to be freely drained from the bottle as and for the purpose specified.

In testimony whereof I affix my signature in presence of two witnesses.

ERNEST C. RIMPLE.
